UNITED STATES PATENT OFFICE.

ERNST MOXTER, OF ST. LOUIS, MISSOURI, ASSIGNOR TO CHARLES O. BORTHE, OF ST. LOUIS, MISSOURI.

ELECTRIC SNAP SWITCH.

Application filed October 10, 1921. Serial No. 506,772.

To all whom it may concern:

Be it known that I, ERNST MOXTER, a citizen of the United States, residing at the city of St. Louis, State of Missouri, have invented a certain new and useful Improvement in Electric Snap Switches, of which the following is a specification, reference being had to the accompanying drawing, forming a part thereof.

10 This invention relates generally to electric switches and, more particularly, to a certain new and useful improvement in electric switches of the so-called snap type.

15 The principal object of my present invention is to provide an efficient electric snap switch of few co-operating preferably sheet-metal parts which may be cheaply and economically manufactured and which may be readily and quickly operatively assembled 20 with a minimum of time and labor.

25 A further object of my present invention is to provide an electric snap switch in which screws or other such means for fastening the members or elements of the switch together are obviated and in which the snap-effecting spring of the switch also functions to mechanically retain the several elements of the switch operatively together.

30 A still further object of my present invention is to cheapen the cost of manufacture, facilitate quantity production, and simplify the construction of and generally improve upon electric switches of the type described.

35 With the above and other objects in view, my present invention resides in the novel features of form, construction, arrangement, and combination of parts hereinafter described and afterwards pointed out in the claims.

40 In the accompanying drawing,

Figure 1 is a perspective view of the frame of the switch;

45 Figure 2 is a perspective view of the rocking-support for the movable blades or terminals of the switch;

Figure 3 is a perspective view of the actuating-member or lever of the switch;

Figure 4 is an elevational view of the spring or yielding-member of the switch.

50 Figure 5 is an enlarged detail sectional elevational view of the connection between one of the switch-blades and its supporting member;

Figures 6, 7, and 8 are, respectively, side,

end, and plan views of an assembled or complete switch embodying my invention; and

Figure 9 is a vertical transverse sectional view of the switch, showing the bearings and spring-connection for the blade-carrying and actuating members of the switch.

Referring now in detail to the said drawing, which illustrates a practical embodiment of my invention and in which like reference characters refer to like parts throughout the several views, 1 designates the base of the switch, which, in practice, may be suitably mounted in a switch box or upon a wall or other support with its outer face flush with the surface of the wall, as is customary.

70 Fixed in spaced relation to and upon the inner face of base 1, are spaced contacts or terminals 2—2 preferably of the spring copper-jaw type, and intermediate the terminals 2—2, base 1 is cut away or recessed, as at 3.

75 Disposed or seated at its bight in recess 3 and suitably secured to base 1, as by screws or the like, not shown, is a frame 4 of substantially U-shape in end elevation, as seen in Figures 1 and 7, the frame 4 being preferably constructed by stamping and forming of a single integral section of suitable stiff or rigid sheet metal.

80 At its bight, frame 4 is cut-away and apertured, as at 5, and formed centrally in the bottom edges of the opposite side walls or legs of frame 4 is a pair of horizontally aligning notches 6—6.

Above the notches 6, the side walls of the frame 4 are further cut-away to provide a pair of horizontally aligning approximately V-shaped openings 7—7, the bases 8 of which are oppositely disposed to, but in vertical alignment with, the notches 6, as best seen in Figure 1, and provide a second pair of

85 notch-bearings, for purposes shortly appearing. In turn above the openings 7, the side walls of the frame 4 are additionally cut-away to provide centrally-disposed open-end assembling slots 9—9 leading into the openings 7, as best seen in Figures 1 and 6.

90 10 designates what may be termed the support for the movable terminals or contacts of the switch, which support is likewise preferably formed by stamping of a single integral section of suitable stiff or rigid sheet metal and comprises a body-portion 11 of

100 approximately inverted U-shape and oppo-

sitely disposed arms 12-12 extending laterally from the legs of the body 11, as best seen in Figure 2, the body 11 being cut-away or otherwise formed at its lower or open end with a pair of oppositely disposed notches 13-13. Each arm 12 is reduced and cut-away at its outer end to provide a shoulder 14 and a fork 15, and fitted intermediate its ends upon such reduced outer end of each arm 12, is a conducting-blade 16. Each respective blade 16, as best seen in Figure 5, is interposed on its carrying arm 12 between retaining-washers 17-17 and suitably insulated both from the washers 17 and the arm 12, as shown, an upsetting or clinching of the prongs of forks 15 upon outer washer 17 simply, yet most efficiently, securely fastening the blades 16 in position upon their supporting member 10. The blades 16, it may be here added, are of such thickness and dimensions to removably fit between and electrically engage with the fixed contacts or jaws 2 when the switch is in circuit-closing position, as best seen in Figures 6 and 8, and while the present switch is equipped with two such blades 16, the switch may equally well include a lesser or greater number of such blades as may meet the requirements of any particular installation.

18 indicates the manipulative element or so-called lever of the switch, which is also preferably constructed by stamping and forming of a single section of suitable stiff or rigid sheet metal and comprises a central portion or body 19, a handle or lever-extension 20 projecting from one or the lower edge of the body 19, a pair of spaced fingers 21-21 projecting from the opposite or upper edge of the body 19 and oppositely bent or offset at their upper free ends to extend laterally out of and upon opposite sides of the plane of body 19, and a pair of oppositely disposed trunnions 22-22 projecting from body 19 intermediate the lever-extension 20 and the fingers 21-21, all as best seen in Figure 3. Fitted upon the lever extension 20 is a handle 23, and I may add that the lever extension 20 is also formed at its lower end with a similar fork 24 which, in a like manner, is clinched upon the handle 23 for securely fastening the same upon the lever 18.

In assembling the several parts of the switch, a blade-support 10 with blades 16 fixed thereupon as described and a lever or manipulative member 18 are first yieldingly attached together by means of a spring 26, one end of the spring being disposed at slot 27 in engagement with the cross or bight-piece of the body 11 of the support 10 and its other end being engaged at aperture 28 with the lever-member 18. The said parts are then inserted, with the lower or free end of lever 18 presented downwardly, between the spaced walls of frame 4 and support 10

engaged or rested at its notches 13 for rocking movement within the apertures 7 and relatively to the frame 4 upon the base-notches 8 of the apertures 7, the open-end slots 9 of frame 4 easily accommodating such edgewise positioning of the support 10. The lever-member 18 is now obliquely tilted for downward movement through aperture 5 and then pulled downwardly against the tension of spring 26 to bring its trunnions 22 below the lower pair of notches 6, when pull upon the lever-member 18 is somewhat released and member 18 sprung into engagement at its trunnions 22 with the notches 6 also for rocking movement relatively to the frame 4. It will be noted, Figure 6, that base 1 is formed at its recess 3 with an aperture 25. The frame 4, with the switch-members proper fitted operatively thereupon as described, is now fitted and secured in recess 3 and the lever-end 24 projected downwardly for manipulation through said base-aperture 25, as clearly seen in Figure 6. It may be added here that base-aperture 25 is of a less width than the lever-member 18 at its trunnions 22 and, consequently, with the parts assembled as described, the base 1 functions also to prevent disruption of the switch proper or breaking of the spring 26 by any unusual outward pull upon the lever-member 18. It may be further added that, as seen best in Figures 7 and 8, the free ends of the upwardly or outwardly presented legs or side-walls of frame 4 are preferably stayed by cross-pins 29.

In operation, as the lever-handle 23 is manipulated or rocked, one or the other of the fingers 21 is brought into positive pushing engagement with the body 11 of blade-support 10 and a limited positive starting movement of the member 10 thus effected and the spring 26 put under further tension, when, on continued movement of lever 18, the spring 26 functions to "snap" or rapidly rock the member 10 and its carried blades 16 to either circuit-opening or circuit-closing position, as the case may be.

It will be seen particularly in Figure 9 that the blade-carrying member 10 is of a width greater than the spacing of the side-walls of frame 4 and that consequently its rocking-travel or movement is limited by the dimensions of the openings 7.

My new switch has been found exceedingly efficient. It is composed of few parts and those parts, with the exception of spring 26, substantially unbreakable and easily and inexpensively manufactured, and the switch as a whole may be most readily and conveniently assembled in a minimum of time and with a minimum of labor. The spring 26 serves not only as a means for effecting rapid or "snap" movement of the conducting blades 16 into and out of circuit-closing position, but also as a mechanical connection for

operatively maintaining both the blade-support 10 and lever 18 in operative detachable relation to each other and to the main frame 4, the parts of the switch proper being readily, when detached from base 1, taken apart for replacement or repair on a mere detachment or disengagement of the spring 26.

I am aware that minor changes in the form, construction, arrangement, and combination of the several parts of the switch may be made and substituted for those herein shown and described without departing from the nature and principle of my invention.

Having thus described my invention, what I claim and desire to secure by Letters Patent is:

1. An electric snap-switch including, in combination, a frame comprising a pair of spaced rigid walls having aligning apertures, a member having engagement with said walls at said apertures for rocking movement in said apertures and between the walls, rigid arms on said member projecting outwardly at approximately right angles to the opposite outer faces of said walls, contact-blades carried by said arms, and means including a spring having engagement with said member for imparting snap rocking-movement to said member and its carried blades, the snap-movement of said member and its carried blades being limited by engagement of said member with the walls at the opposite sides of said apertures.

2. An electric snap-switch including, in combination, a frame comprising a pair of spaced rigid walls having aligning substantially V-shaped apertures, a substantially U-shaped member having engagement between the outer ends of its legs and the bases of said apertures for rocking movement in said apertures and between the walls, oppositely-disposed rigid arms on the legs of said member projecting outwardly at approximately right angles to the opposite outer faces of said walls, contact-blades carried by said arms, and means including a spring having engagement with said member for imparting snap rocking-movement to said member and its carried blades, the snap-movement of said member and its carried blades being limited by engagement of said member with the walls at the opposite sides of said apertures.

3. An electric snap-switch including, in combination, a frame comprising a pair of spaced rigid walls having oppositely-disposed aligning pairs of notches and substantially V-shaped apertures, a substantially U-shaped member having engagement between the outer ends of its legs and the bases of said apertures for rocking movement in said apertures and between the walls, contact-blades carried by said member, and means for imparting snap rocking-

movement to said member and its carried blades, said means including a lever having rocking-engagement at said notches with said walls, and a spring having engagement with the lever and with said member.

4. An electric snap-switch including, in combination, a frame comprising a pair of spaced rigid walls having aligning apertures, a member having engagement with said walls at said apertures for rocking movement in said apertures and between the walls, rigid arms on said member projecting outwardly at approximately right angles to the opposite outer faces of said walls, contact-blades carried by said arms, and means for imparting snap-rocking-movement to said member and its carried blades, said means including a lever having engagement with said walls for rocking-movement, a spring having engagement with the lever and with said member, and oppositely-disposed fingers on the lever adapted for pushing engagement with the member.

5. An electric snap-switch including, in combination, a frame comprising a pair of spaced walls having a pair of aligning apertures and a pair of aligning notches, a member having engagement with said walls at said apertures for rocking movement in said apertures and between the walls, contact-blades carried by said member, and means for imparting snap-rocking-movement to said member and its carried blades, said means including a lever having rocking engagement at said notches with said walls, a spring having engagement with the lever and with said member, and oppositely-disposed off-set fingers on the lever adapted for pushing engagement with said member.

6. An electric snap-switch including, in combination, a frame comprising a pair of spaced rigid walls having oppositely-disposed aligning pairs of notches and substantially V-shaped apertures, a substantially U-shaped member having support at the outer ends of its legs upon said walls for rocking-movement in said apertures and between the walls, rigid arms on said member projecting outwardly at approximately right angles to the opposite outer faces of said walls, contact-blades carried by said arms, and means for imparting snap-rocking-movement to said member and its carried blades, said means including a lever having rocking engagement at said notches with said walls, a spring having engagement with the lever and with said member, and oppositely-disposed off-set fingers on the lever adapted for pushing engagement with said member, the snap-movement of said member and its carried blades being limited by engagement of said member with the walls at the opposite sides of said apertures.

7. An electric snap-switch including a substantially U-shaped frame provided in

- its opposite walls with a pair of substantially V-shaped apertures, the base of said apertures forming notch-bearings, a blade-carrying support disposed in said apertures and mounted on said bearings for rocking movement relatively to the frame, the frame being also apertured in its base and provided with a pair of notch-shaped bearings oppositely disposed to the first-named bearings, and means for rocking the support, said means comprising a separate lever projecting through said base aperture and having rocking-engagement with the second pair of notches, and a spring for imparting snap movement to the support having engagement at its opposite ends with the support and with the lever, the rocking movement of the support being limited by the opposite walls of said V-shaped apertures.

10 8. An electric snap-switch including, in combination, a substantially U-shaped stamped metal frame provided in its opposite side walls with a pair of substantially V-shaped apertures, the base of said apertures forming notch-bearings, a substantially U-shaped stamped metal blade-support mounted for rocking-movement in said apertures and having engagement with said notches, a pair of oppositely disposed blade-carrying arms projecting through said apertures and movable with said support, said frame being also apertured in its base and provided with a second pair of notches oppositely disposed to the first pair of notches, and means for rocking said blade-carrying support, said means comprising a stamped metal lever projecting through said base-aperture and having engagement for rocking movement with the second pair of notches, and a spring for imparting snap movement to the support having engagement at its opposite ends with the support and with the lever, the rocking movement of the support being limited by the opposite walls of said V-shaped apertures.

15 9. An electric snap switch including, in combination, a frame comprising a pair of spaced rigid walls having a pair of aligning apertures and a pair of aligning notches, said notches being oppositely disposed to the bases of said apertures, a substantially U-shaped member having detachable engagement between the outer ends of its legs and the bases of said apertures for rocking-movement in said apertures and between the walls, contact-blades carried by said member, a lever having detachable rocking engagement at said notches with said walls, and a spring having detachable engagement with the lever and with said member, said spring providing a yielding snap connection between the lever and the member and a mechanical connection for securing the lever and member in operative engagement with the frame.

20 10. An electric snap-switch including, in combination, a frame comprising a pair of spaced rigid sheet metal walls having oppositely disposed aligning pairs of notches and substantially V-shaped apertures and open slots leading into said apertures, a substantially U-shaped sheet metal member having detachable engagement between the outer ends of its legs and the bases of said apertures for rocking movement in said apertures and between the walls, contact-blades carried by said member, a sheet metal lever having detachable rocking engagement at said notches with said walls, and a spring having detachable engagement with the lever and with said member, said spring providing a yielding snap connection between the lever and the member and a mechanical connection for detachably securing the lever and member in operative engagement with the frame and said slots accommodating assembly of said member into and out of said apertures.

25 11. An electric snap-switch including a base and a pair of fixed terminals on the base, in combination with a frame comprising a pair of spaced rigid walls mounted on the base between said terminals, said walls having a pair of aligning apertures and a pair of aligning notches oppositely disposed to the bases of said apertures, a substantially U-shaped member having support at the outer ends of its legs upon the bases of said apertures for rocking-movement in said apertures and between the walls, contact-blades carried by said member for releasable engagement with said contacts, and means for rocking said member and its carried blades, said means comprising a lever disposed between the walls and projecting outwardly through the base, the lever having rocking engagement at said notches with said walls, and a spring having engagement with the lever and with said member, the snap-movement of said member and its carried blades being limited by engagement of said member with the walls at the opposite sides of said apertures.

30 In testimony whereof, I have signed my name to this specification.

35 ERNST MOXTER

In testimony whereof, I have signed my name to this specification.

ERNST MOXTER.
